UNITED STATES PATENT OFFICE.

FRANK L. HUNTOON, OF ROBINSON, ILLINOIS.

DESIGN FOR A COMBINED BED OR COUCH AND DESK CABINET.

47,535.

Specification for Design.

Patented July 6, 1915.

Application filed December 14, 1914. Serial No. 877,251. Term of patent 14 years.

To all whom it may concern:

Be it known that I, FRANK L. HUNTOON, a citizen of the United States, residing at Robinson, in the county of Crawford and State of Illinois, have invented a new, original, and ornamental Design for a Combined Bed or Couch and Desk Cabinet, of which the following is a specification, reference being had to the accompanying drawings, forming a part thereof.

The figure shows the article in perspective as viewed diagonally, the desk cabinet being shown closed.

I claim—

The ornamental design for a combined bed or couch and desk cabinet substantially as shown.

FRANK L. HUNTOON.
